CLAIM

The ornamental design for a contact lens inserter, as shown and described.

DESCRIPTION

FIG. 1 is a perspective view of a contact lens inserter showing my new design;

FIG. 2 is a bottom perspective view thereof;

FIG. 3 is a top plan view thereof;

FIG. 4 is a bottom plan view thereof;

FIG. 5 is front elevational view thereof, the rear elevational view being a mirror image;

FIG. 6 is a right side elevational view thereof; and,

FIG. 7 is a left side elevational view thereof.
